HORSESHOE-CALKING MACHINE.

1,169,059.

Specification of Letters Patent.

Patented Jan. 18, 1916.

Application filed March 4, 1915. Serial No. 12,161.

To all whom it may concern:

Be it known that I, JOHN M. WATSON, a citizen of the United States, residing in the city of Omaha, county of Douglas, and State of Nebraska, have invented certain new and useful Improvements in Horseshoe-Calking Machines, and have described the same in the following specification, illustrated by the accompanying drawings.

10 My invention relates to that class of forging machines which are individually adapted not only to form the heel calks of a horseshoe by bending a heated horseshoe blank, but also, without reheating, to shape and 15 finish the calks so formed.

It is the object of my improvements to produce a simple, compact, serviceable, convenient and superior machine of this class.

Accordingly the invention resides in the 20 combination and arrangement of the parts of the machine, and in the details of construction hereinafter described and claimed.

In said drawings, illustrating the best manner in which I have contemplated applying the principles of the invention, Figure 1 is a rear elevation of a horse-shoe calking machine which is constructed in accordance with these principles. Fig. 2 is a 25 side view of the same machine, partly in elevation and partly in vertical section on the section line 2—2 of Fig. 1. Fig. 3 is a vertical section on the broken line 3—3 of Fig. 2. Fig. 4 is a horizontal section on the broken line 4—4 of Fig. 3, parts being 30 shown positioned as in Fig. 1. Fig. 5 is a vertical section on the broken line 5—5 of Fig. 4. Figs. 6 to 11 inclusive, are details in perspective. Fig. 6 shows the plunger carrying the wedge and two hammers. Fig. 7 shows an inside die and an outside die which 35 engage one limb of the shoe. Fig. 8 shows in a modified form the two dies which correspondingly engage the other limb of the shoe. Fig. 9 is a clamping member for holding 40 the shoe in position on the table. Figs. 10 and 11 are modifications of Fig. 9. Fig. 12 is a plan of the table. Fig. 13 is a modification of Fig. 6.

In the illustrated specimen of my invention the frame of the machine comprises 45 two vertical standards 1, which are rigidly connected by the horizontal table 2, on which the shoe 29 is to be laid in the position shown. These standards have in their proximate faces a pair of vertical grooves

6 facing toward each other. They are also provided with rear extensions, or brackets 4 having a similar pair of grooves 5. In the bearings 7, formed in this frame, is journaled the shaft 8, which is understood to be 60 rotated, either continuously or interruptedly as may be desired, to operate the machine. On this shaft is keyed the disk 9, having the wristpin 10, actuating by the connecting rod 46 the vertically reciprocable slide block 27 65 on the plunger stem 11. The plunger actuated by this stem comprises the vertically disposed metallic plate 13 and a pair of alining metallic rollers 12, the latter being mounted on the shaft or pin 14 along the 70 upper margin of the plate. This plunger is vertically reciprocable in and between the guiding grooves 5, and between the table 2 and the crossbar 3; while this bar is secured to the brackets 4 and adjustable toward and 75 from the table 2 by the screws 47. The plunger stem 11 carries the fixed collar 28 for occasional engagement with the slide block 27, and has the latch 15. This latch is actuated by the spring 16 and the bell-crank lever 17 to hold up the plunger when raised to the position shown in Fig. 2, and to release the stem and let down the plunger to the position shown in Fig. 1, whenever the roller 18, carried by that lever, is 80 engaged by the wedge knob 19 projecting from the periphery of the disk 9. On the same shaft 8 is keyed an eccentric having the strap 20 actuating the connecting rod 21 and the plunger stem 22. This stem carries the wedge 23, and preferably has also the hammers 25 which are adapted to press down formatively upon the upper ends of both calks in position upon the table. These hammers, however, are to be structurally 85 omitted from the mechanism, as shown in Fig. 13, in case the calks to be formed are of the sharp pattern shown in Fig. 10. The same stem preferably carries also the terminal guiding extension or stem 24. The 100 plunger stem 22 works through a guiding hole in the bracket 26, while the guiding stem 24 works in the vertical hole 48 through the table 2.

The holder 30 for clamping the shoe 105 down on the table 2, comprises a pair of duplicate side bars, denoted by the same numerals 30, and flexibly connected by the crossbar 31. These bars, being adapted to reciprocate vertically in unison in the 110

grooves 6 and in the guiding holes 49 perforating the table 2, are bent over toward each other at the top, above the table, and then downward, forming the clamps 34, 5 which are adapted to hold down the shoe and to shape the forward faces of the calks, being operated by the connecting-rod 33 and the foot-lever 32 with its detaining catch 50. These clamps may be of varied 10 interchangeable forms, 34, 35 and 36, according to the patterns of the calks which are to be shaped against them.

On the table 2 are seated two pairs of spaced, alining and laterally movable dies, 15 37, 38, 39 and 40. The outer dies 37 and 40 are similar to each other, and individually carry the downwardly projecting screw 41, which is adapted to be moved laterally in the guiding slot 51 perforating the table. 20 By means of the nut 42 on the free end of this screw under the table, these two dies, being shaped in conformity with the outside of the shoe, and being manually adjusted at a suitable distance apart according to the 25 width of the shoe, are set immovably as adjusted and shown. Each of the inner dies 38 and 39, which are similar to each other, has a guiding leg 43, having the retaining shoe 52 and working by lateral 30 translation in the slots 44, which perforate the table. These two dies, when not separated by the wedge 23, are approximated by the compression springs 45 to release the shoe. These dies, 37, 38, 39 and 40, may be 35 made in various modified forms, according to the pattern of the shoe and calk, and according as the shoe is the right or left member of a pair of shoes of that pattern; and may be readily interchanged with the 40 modifications, as for example, dies 39 and 40 with the modified forms 46 and 47' respectively.

Operatively the shoe to be calked, being suitably heated for forging, is laid flat on the table between and contacting with the fitted and preadjusted external dies 37 and 40, and outside the internal dies 38 and 39, but with its calkable ends jutting over the rear margin of the table across the path of the bender. In this position the shoe is to be adjusted in abutting contact with the crossbar 3, preadjusted by the screws 47 as a stop gage, according to the length of the calks to be formed. Then by operating the 55 foot-lever the shoe is gripped by the clamps 34 in the position shown in Fig. 4, and is held firmly in that position by the lever catch 50. Then by the rotation of the power shaft and the resulting upward movement 60 of the plunger stem 11, the bending rollers and the die-plate are lifted from the position shown in Fig. 1 to that shown in Fig. 2, where they are caught and held by the action of the latch 15, and there sustained 65 until let go by that latch. Thereby the

calks are bent up by the rollers 12, and the die-plate 13 is snugly positioned against the calks as shown in Fig. 2. Meanwhile the plunger stem 22, actuated by the eccentric, and actuating the wedge 23, forces the dies 70 38 and 39 apart and against the calks, and then drives the hammers formatively down upon the ends of the calks. Thereby the calks, softened by heat and bent up as described, are subjected simultaneously to lateral compression between the inner and the outer dies, to antero-posterior compression between the clamp 34, 35 or 36, and the die-plate 13, and to vertical compression 75 between the hammers and the table; whereby 80 the calks are completely formed, and finished at every bounding surface. As the rotation of the power shaft then continues, the plunger 22 lifts the hammers 25 clear of the calks and relieves the inner dies from the separating pressure of the wedge; while the plunger stem 11, being unlatched by the movement of the bell-crank lever, drops the bending rollers and the die-plate to the inoperative position below the level of the 85 table, as shown in Fig. 1. The dies 38 and 39 are then pushed inward clear of the shoe by the springs 45. Then by a movement of the foot-lever the clamps 34 are lifted away from the shoe, which may then 90 be removed from the machine to make way for its successor.

I claim as my invention—

1. A calking machine of the specified class, comprising a table on which the shoe 100 is to be laid, means for clamping the shoe to the table, a pair of movable outside dies seated on the table, means for setting these dies at a variable distance apart equal to the width of the shoe between them, a pair 105 of inside dies secured to the table, means for guiding the inside dies, a plunger actuating the inside dies to engage the shoe, a bender and a die-plate which are vertically reciprocable at the margin of the table, and a plunger actuating the bender and the die-plate.

2. A calking machine of the specified class, comprising a table for the support of the shoe, a stop gage spaced an adjustable distance from the table, and means for clamping the shoe to the table in a location regulated by the adjustment of the gage.

3. A calking machine of the specified class, comprising a table for the support of the shoe, a pair of vertically reciprocable clamping members working through the table to engage the limbs of the shoe respectively, a link connecting the clamps, and an actuating lever connected with the link.

4. A calking machine of the specified class, comprising a table for the support of the shoe, a block movable vertically above the table, means for adjusting the block to clamp the shoe to the table, and means for

afterward pressing the upturned shoe calk formatively forward against the clamping block.

5. A calking machine of the specified class, comprising a table for the support of the shoe, a plunger working vertically through a hole in the table, and carrying a pair of hammers adapted formatively to engage the end surfaces of the calks respectively and means for compressing horizontally against the hammers the shoe-calks in process of formation.

6. A calking machine of the specified

class, comprising a table for the support of the shoe, means for clamping the shoe to the table, a pair of movable dies attached to the table, and a plunger working through a hole in the table to spread the dies to engage the shoe so clamped.

In testimony whereof I subscribe this specification in the presence of two witnesses.

JOHN M. WATSON.
